UNITED STATES PATENT OFFICE.

CHARLES E. GOULD, OF LEOMINSTER, MASSACHUSETTS, ASSIGNOR TO THE GOULD ROLLING MACHINE COMPANY, OF SAME PLACE.

MACHINE FOR MAKING ROLLED FORGINGS.

SPECIFICATION forming part of Letters Patent No. 412,383, dated October 8, 1889.

Application filed August 14, 1889. Serial No. 320,725. (No model.)

To all whom it may concern:

Be it known that I, CHARLES E. GOULD, of Leominster, in the county of Worcester, State of Massachusetts, have invented a certain new and useful Improvement in Machines for Making Rolled Forgings, of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved machine; Fig. 2, a sectional elevation taken on the line $x-x$ in Fig. 1; Fig. 3, a like view on the line $y-y$ in Fig. 1, and Fig. 4 an enlarged sectional view showing the formation of the working-face of the dies.

Like letters and figures of reference indicate corresponding parts in the different figures of the drawings.

My invention relates to that class of machines for making rolled forgings in which one forming-die moves over or past the other while in contact with the bar being acted upon; and it consists in certain novel features, as hereinafter fully set forth and claimed, the object being to produce a simpler, cheaper, and more effective device of this character than is now in ordinary use.

The nature and operation of the improvement will be readily understood by all conversant with such matters from the following explanation:

In the drawings, A represents the bench or frame-work of the machine, which consists of a bed-piece b , supported by standards or legs d , connected by braces f . The bed or table b is provided in its upper face with two longitudinally-arranged V-shaped tracks or grooves g and centrally with a rectangular groove or track h . A platen B is provided on its under face with two V-shaped flanges i , fitted to work in the tracks g , and centrally with a cross-sectional rectangular flange j , working in the track h . The lower edge of the flange j is toothed at k , forming a rack.

A horizontal rotating shaft l is journaled in the bench A and a standard m , said shaft bearing fast and loose pulleys p q , whereby

a reciprocating movement may be imparted by means of a crossed and straight belt and shipper in the ordinary manner.

A horizontal rotating shaft r is journaled centrally in the table b and bears a gear t at 55 its outer end, meshing with a pinion v on the shaft l . A centrally-arranged pinion w on the shaft r meshes with the rack j on the platen B . A stub-shaft 15 is journaled in a block 16 , secured centrally to the rear edge of 60 the table b , said shaft bearing a pinion 17 , meshing with a longitudinally-arranged rack 18 , at the rear edge of the platen B . A shaft 19 is journaled in standards 20 and 21 , secured centrally at the front and rear edges of 65 the table, said shaft bearing a large gear 22 , which meshes with the pinion 17 . The bearing of the shaft 19 in the standard 21 is cushioned on a spring 23 and is adjustable 70 vertically by means of a set-screw 24 , which passes through the top of said standard.

A horizontal die C is secured to the face of the platen B , and consists of a bed-piece 25 , provided with a vertically-inclined working-face 26 . The face 26 comprises two cutting 75 flanges or bosses 27 , the outer edges of which incline outwardly (see Fig. 4) at 28 and diverge gradually from the lower end 29 of said face to its highest end 30 . The face between the bosses 27 is grooved longitudinally at 31 80 to conform to the shape of the article to be rolled, (see Fig. 4,) said article being in the present instance a tool-handle.

A broad wheel 32 is secured to the shaft 85 19 and bears a die D , consisting of a curved bed-plate 33 , provided with a working-face 35 , constructed in the same form and of the same size as the die C , said die D being, however, as shown, convex in longitudinal section. The dies are disposed in the same vertical 90 plane, with their cutting-bosses 27 and 36 registering with the ends 29 and 30 of the die C , being disposed diametrically opposite the corresponding ends 37 and 38 of the die D , and their working-faces being of the same 95 length.

In the use of my improvement the shaft l , being set in motion, rotates the shaft r and drives the platen B horizontally in the tracks g . As the platen moves, the rack 18 rotates 100

the shaft 19 and causes the die-wheel 32 to revolve in a direction opposite to that in which the platen moves. A bar H, from which the forging is to be rolled after being 5 properly heated, is passed through an opening 40 in the standard 21, which serves as a guide, therefor, and laterally between the dies C D as their ends 29 and 37 of their respective working-faces approach each other. 10 The cutting-bosses of the dies engage said bar on opposite sides, and as they pass each other form the handle 50, or other article to which the dies are adapted, in a manner readily understood by all conversant with 15 such matters. The bar is rotated by the action of the dies as they pass. By indenting or corrugating the beveled faces 28 of the bosses this rotation is made more regular, and the article thus formed is more perfect in shape. The bosses bisect the bar at each end of the forging, a waste piece 51 falling onto the platen, from which it may be readily removed. One end of the shaft 19, resting on the spring 23, depresses it slightly 20 when not in action, thus affording sufficient play to easily insert the bar. The reciprocating movement completes the formation of the article much more perfectly than when the wheel completely revolves and avoids the 25 necessity of directing the bar for the subsequent movements of the dies.

Having thus explained my invention, what I claim is—

1. In a machine for making rolled forgings, companion forming-dies having, respectively, a horizontal and rotary movement, substantially as described.
2. In a machine for making rolled forgings, a horizontally-moving bed-die and a vertically-rotating companion die, substantially as set forth.
3. In a machine for making rolled forgings, companion forming-dies comprising a horizontally-reciprocating bed-die and a vertically-reciprocating rotary die, substantially as described.
4. In a machine for making rolled forgings, a horizontal bed-die and a vertically-rotating companion die moving in opposite directions, substantially as set forth.
5. In a machine for making rolled forgings, a horizontally-moving platen bearing a bed-die and driving a rotating shaft bearing a wheel provided peripherally with a companion die convex in longitudinal section, substantially as described.
6. In a machine for making rolled forgings, a body, a platen sliding horizontally thereon, a bed-die on said platen, a rotary shaft geared to the platen, a die-wheel on said shaft, and a convex die on said wheel registering with said bed-die, substantially as set forth.
7. In a machine for making rolled forgings, a body, a platen sliding horizontally thereon, a rotary shaft, a wheel thereon bearing a convex die registering with a bed-die on said

platen, and mechanism for reciprocating the platen, substantially as described.

8. In a machine for making rolled forgings, a body, a horizontally-sliding platen provided with a rack, a shaft having a pinion meshing therewith and geared to the driving-shaft, a rack on the upper face of the platen, a shaft provided with a die-wheel and gear, a stub-shaft having a pinion meshing 75 with said gear and rack, a horizontal die on the platen, and a convex die on the wheel, substantially as described.

9. In a machine for making rolled forgings, the dies C D, in combination with the body 80 A, platen B, shaft 19, bearing the wheel 32 and gear 22, and mechanism, substantially as specified, for reciprocating said shaft and platen.

10. In a machine for making rolled forgings, a body, a horizontally-sliding platen bearing a bed-die and driving a shaft having an adjustable journal, a wheel on said shaft bearing a companion die convex in longitudinal section, and mechanism for reciprocating said platen, whereby said dies are moved in opposite directions in the same vertical plane, substantially as described.

11. In a machine for making rolled forgings, a bed-die fixed to a horizontally-moving 95 platen, said die having longitudinally-diverging and vertically-inclined cutting-bosses, in combination with a companion die having a similarly-constructed working-face convex in longitudinal section and arranged to 100 rotate vertically, substantially as described.

12. In a machine for making rolled forgings, a horizontally-reciprocating bed-die and vertically-reciprocating rotary companion die, said dies moving in opposite directions in the 105 same vertical plane and provided with longitudinally-diverging vertically-inclined cutting-bosses, substantially as described.

13. In a machine for making rolled forgings, a horizontally-reciprocating bed-die 110 and a vertically-reciprocating rotary companion die, said dies being provided with working-faces comprising longitudinally-diverging vertically-inclined cutting-bosses having outwardly-inclined spreading faces, substantially 115 as described.

14. In a machine for making rolled forgings, a horizontally-reciprocating bed-die and a vertically-reciprocating rotary companion die convex in longitudinal section, said dies 120 having longitudinally-diverging vertically-inclined cutting-bosses arranged in diametrically-opposite positions, substantially as described.

15. In a machine for making rolled forgings, a body, a horizontally-sliding platen bearing a bed-die and driven by a pinion on a shaft geared to a driving-shaft, means for reciprocating said driving-shaft, a rotating shaft journaled in standards above said 125 platen and geared thereto to revolve in an opposite direction, and a wheel on said shaft 130

bearing a companion die convex in longitudinal section, substantially as described.

16. A machine for making rolled forgings, having a horizontally-reciprocating bed-die and vertically-reciprocating rotary companion die, said dies moving conjointly in diametrically-opposite directions and in the same vertical plane, substantially as described.

17. In a machine for making rolled forgings, a body, a reciprocating driving-shaft, an intermediate shaft geared thereto, a horizontally-sliding platen having a rack meshing with a pinion on said shaft, a stub-shaft and pinion meshing with a rack on said platen, and a gear on a rotary shaft journaled in

standards above said platen, a bed-die on the platen, and a wheel on the rotating shaft bearing a convex companion die, substantially as described.

18. The body A and reciprocating platen B, bearing the die C, in combination with the shaft 19, geared to said platen to move in opposite directions thereto, the wheel 32 on said shaft, and the convex die D, secured on said wheel, all being arranged to operate substantially as described.
